UNITED STATES PATENT OFFICE.

ALBERT HERMAN CLAUS, OF PORTLAND, OREGON.

HATPIN.

1,408,722.

Specification of Letters Patent. Patented Mar. 7, 1922.

Application filed September 22, 1921. Serial No. 502,374.

To all whom it may concern:

Be it known that I, ALBERT HERMAN CLAUS, a citizen of the United States, and a resident of Portland, in the county of

5 Multnomah and State of Oregon, have invented certain new and useful Improvements in Hat Pins, of which the following is a specification.

My invention relates to hat pins and the 10 purpose of my invention is the provision of a hat pin of extremely simple and inexpensive construction which can be readily applied to the hair and hat for securely retaining the hat to the hair, and at the same 15 time permitting the ready withdrawal thereof when removing the hat.

I will describe one form of hat pin embodying my invention and will then point out the novel features thereof in 20 claims.

In the accompanying drawings:

Figure 1 is a view showing a hat in bottom plan and having applied thereto one form of hat pin embodying my invention.

25 Figure 2 is an enlarged detail perspective view of the hat pin shown in Figure 1.

Referring specifically to the drawing, in which similar reference characters refer to similar parts, the hat pin in its present embodiment comprises a single length wire or other suitable material curved longitudinally in the form of an arc to provide a body portion 16, and having one end bent rearwardly upon itself to provide a substantially U-shaped gripping portion 17 and a penetrating portion 18 extending substantially at right angles from the portion 17 and terminating in a point 19. Both portions 17 and 18 are disposed in the same plane as the 40 body portion 16.

In the applied position of the hat pin as shown in Figure 1, the longitudinally curved portion 16 is designated to penetrate the hair, and the curvature of this portion 45 is such as to conform to the shape of the head so as to secure the pin against longitudinal displacement from the hair. The penetrating portion 18 is gripped at the portion 17 and forced into the brim of the

hat so as to lie substantially parallel to the 50 brim so that it prevents lateral displacement of the curved portion 16 from the hair.

In practice, two or more of the hat pins are adapted to be used in retaining a hat 55 upon the head, and these pins are applied in the manner shown in Figure 1, and in the application of each pin it is caused to penetrate the hair before applying the hat, and when the hat is in position upon the head 60 the portion 18 is inserted into the brim of the hat so that the pin will be locked in the hat. The removal of either pin can be readily effected without disturbing the arrangement of the hair by holding the hat and withdrawing the portion 18 until it is disengaged from the brim.

Although I have herein shown and described only one form of hat pin embodying my invention, it is to be understood that 70 various changes and modifications may be made herein without departing from the spirit of the invention or the spirit and scope of the appended claims.

What I claim is:

1. A hat fastener formed from a single length of wire curved longitudinally to conform to the curvature of the head and to provide a hair engaging portion, and rear portion of said length of wire being 80 formed with a bend defining a gripping portion and a laterally projecting brim engaging pin, said brim engaging pin being adapted to lie parallel to the brim whereby to hold the hair engaging portion against 85 longitudinal movement.

2. A hat fastener formed from a length of wire curved longitudinally to provide a hair engaging portion, the rear portion of said length of wire being formed with a 90 bend defining a gripping portion arranged entirely on one side of the hair engaging portion and defining a lateral projecting brim engaging pin—arranged on same side of the hair engaging portion, said brim engaging portion being adapted to lie parallel to the brim when engaged therewith.

ALBERT HERMAN CLAUS.
